[57] CLAIM

The ornamental design for a combined desk set, clock and calendar holder, as shown and described.

DESCRIPTION

FIG. 1 is a perspective view of a combined desk set, clock and calendar holder showing my new design;

FIG. 2 is a top plan view, thereof;

FIG. 3 is a front elevational view, the rear being substantially a mirror image thereof;

FIG. 4 is a right side elevational view; and
FIG. 5 is a bottom plan view.

The portions of the article normally visible through the transparent base and the writing instruments in FIG. 5, as well as a portion of one of the writing instruments in FIG. 3, have been omitted for convenience of illustration.

FIG. 1**FIG. 2****FIG. 3****FIG. 5****FIG. 4**
